Dec. 1561

Walter W. Stanard, of Buffalo, N.Y.
Assignor to
Jewett and Root, of same place.
Letters Patent No. 1561, dated April 1, 1862.

This is to witness and record the design referred to in this Letters Patent and making part of the same.

Will you inform it may concern:

Be it known that I, Walter W. Stanard, of the City of Buffalo, County of Erie and State of New York, assignor to Sherman S. Jewett and Francis H. Root, - firm of Jewett & Root, of the same place have invented or produced a new and original ornamental design for a double door plate stove, and I do hereby declare that the following is a full and clear description thereof reference being had to the accompanying photographic plates and the letters of reference marked thereon, in which -

Fig. 1. represents the front plate and doors.

Fig. 2. the back plate, and

Fig. 3. the side plate.

The front plate Fig. 1, is surrounded by the plain beaded mouldings a. The lower and larger door b, has a plain quarter and half round moulding c, at its sides and bottom and also a corded or twisted moulding d, and at the top of the door is a carved or scroll moulding e. The panel of the door has an emboss of carved scrolls and leaves symmetrically arranged as represented.

The upper corners of the upper door are rounded and the mouldings c & d, of the lower door continue up its sides and across its top. It has a central rosette f, and imbossed scrolls g,

Des. 15601

The back plate Fig. 2, is surrounded by a headed moulding z , similar to that surrounding the front. It has a large rectangular panel j , formed by plain quarter and half round mouldings k , and corded or twisted moulding l , similar to that surrounding the doors of the front plate. and the panel has an embossing of carved scrolls and leaves m , similar to that on the door h , Fig. 1.

The side plate Fig. 3, has a plain moulding n , surrounding it similar to that surrounding the other plates. It has a large oval panel in the centre formed by the plain ogee moulding o . At the four corners of the plate are carved and reticulated embossed scrolls p , and also ornaments q , connecting oval moulding o , with plain moulding n , at the top and bottom.

In the centre of the large oval panel, is an embossed rosette r , surrounded by the carved scrolls and ornaments s . The opposite side plate is the same in all respects. The minute details of the configuration and arrangement of the various ornaments is fully represented in the plates.

I claim the disposition and arrangement of the ornamental devices for the decoration of the plates of a stove as herein described and represented in each of the accompanying photographic plates Figs. 1, 2 & 3.
